UNITED STATES PATENT OFFICE.

EDWARD LESLIE, OF ORANGEVILLE, ONTARIO, CANADA.

BOLT-FASTENING.

SPECIFICATION forming part of Letters Patent No. 240,260, dated April 19, 1881.

Application filed September 10, 1880. (No model.) Patented in Canada August 23, 1880.

To all whom it may concern:

Be it known that I, EDWARD LESLIE, of Orangeville, in the county of Wellington, in the Province of Ontario, Canada, gentleman, 5 have invented certain new and useful Improvements on Bolt-Fastenings, of which the following is a specification.

The object of this invention is to prevent the bolt-connection escaping from the bolt-hole, 10 and thereby severing the connection of the parts, and also by adjustability to allow the bolt to be withdrawn, when required, to separate the parts connected, such as thill-couplings, &c.; and my invention consists of a 15 device fixedly attachable to a portion of the vehicle near the bolt-head, and composed of a suitable plate having jaws which interpenetrate other jaws on the end of an arm whose opposite end rests in contact with the bolt-head, 20 a latch-piece engaging with one of said jaws, and a cylindrical rubber spring, the whole secured operatively together by a pintle, whereby the latch-piece, when raised from its catch, 25 compresses the spring and allows the arm to turn on the pintle clear of the bolt-head for the removal of the bolt when required.

Figure 1 is a perspective view of my fastener applied to a thill-coupling in latched position to hold the bolt. Fig. 2 is a like view, 30 showing the same unlatched for withdrawal of the bolt. The other figures show the parts detached.

A is the plate, of any suitable form adapted to the place of application, and fixed thereto 35 by screws or other fastenings, the location being near the head of the bolt to be fastened. The plate A is constructed with fixed jaws *a a*, having holes through which to pass a pintle.

B is an arm, constructed at one end with jaws *b b*, the other end terminating in a swell, 40 *c*, which opposes the bolt-head.

C is an elbow-latch, and D a cylindrical rubber spring.

The jaws *a a* and *b b* have the same intervening space, and when overlapped are hinged together by a pintle or pin, *d*, which also passes through one arm of the latch and rubber cylinder longitudinally, the latter being placed between one of the jaws *a*, and the arm of the 45 latch-piece within one of the jaws *b*, the other jaw *b* having a recess, *e*, which receives one arm of the latch C, which latter also has notch *f* to catch with the recess *e* when the arm is in contact with the bolt-head. The resilience of the rubber springs keeps both parts 50 in latched contact, whereby the arm B will be rigidly held to oppose the escape of the thill-bolt E. The latch-piece C projects over the jaw, and forms a hold for the thumb and finger to lift the latch out of engagement with its catch on the jaw *b*, whereby the arm B can be swung clear of the bolt-head to allow the bolt to be withdrawn when required. The latch-piece 55 C being elbow-shaped, when the catch-end is raised to release the bolt, as before described, the other end acts as a lever on the rubber spring to compress it, the expansion of the spring keeping the latch and catch in engagement for securing the bolt, as previously 60 described.

I claim as my invention—

1. A bolt-fastening device consisting of the combination of plate A, having jaws *a a*, arm B, having jaws *b b*, elbow-latch C, and spring 75 D, operatively connected by pintle *d*, in the manner and for the purpose set forth.

2. The latch C and spring D, in combination with the arm B, having jaws *b b*, and plate A, having jaws *a a*, pintled together, as set forth.

EDWARD LESLIE.
